UNITED STATES PATENT OFFICE.

RUTH MACKAY, BELMONT, MASSACHUSETTS.

HEAD FOR RAG DOLLS.

Application filed May 6, 1925. Serial No. 28,485.

To all whom it may concern:

Be it known I, RUTH MACKAY, a citizen of the United States, residing at Belmont, county of Middlesex, State of Massachusetts, have invented a certain new and useful Improvement in Heads for Rag Dolls, of which the following is a specification, reference being had therein to the accompanying drawings.

10 My invention relates to the making of heads for rag dolls, that is, to a type of doll having a face of cloth or other elastic fabric stuffed with cotton or similar soft fibrous material. The particular object of 15 the invention is to produce a doll having a more life-like expression than dolls as heretofore constructed.

The invention will be fully understood from the following description when taken 20 in connection with the accompanying drawings, and the novel features thereof will be pointed out and clearly defined in the claims at the close of this specification.

In the drawings:

25 Fig. 1 is a side elevation of a foundation pad on which the head is constructed.

Fig. 2 is a front elevation of the foundation pad shown in Fig. 1.

Fig. 3 shows the forehead pad applied.

30 Fig. 4 shows the cheek pads applied.

Fig. 5 shows the nose pad applied.

Fig. 6 shows the lip pad applied.

Fig. 7 shows the chin pad applied.

Fig. 8 shows the built-up stuffing covered 35 with elastic material such as Jersey cloth.

Fig. 9 is a side elevation of the doll's head at the stage shown in Fig. 8.

Fig. 10 shows the eye stitches applied.

Fig. 11 shows the nose stitches applied.

40 Fig. 12 shows the mouth stitches applied.

Fig. 13 shows the fastening for the elastic covering removed and the additional cheek and chin stuffing inserted.

Fig. 14 shows the wig and brain stuffing.

45 Fig. 15 is a section on line 15—15, Fig. 14.

Fig. 16 is a side elevation of the head after the features are painted in.

Fig. 17 is a front elevation of the completed head.

50 Referring now to the drawings:

The formation of the head of a rag doll and the construction of the doll itself will be readily understood from a description of the successive steps by which the head is 55 produced. I first make a small foundation pad 11 (see Figs. 1 and 2) by stuffing a

small piece of Jersey cloth or other suitable material with some suitable fibrous material, such as cotton, wool or kapok, the edges of the cloth being folded in and secured on the back side by stitching or otherwise as indicated at 12.

I then make a small wad 12 of the fibrous material (see Fig. 3) and place it across the front of the foundation pad 11 to form the forehead. The forehead pad 12 covers the upper half of the foundation pad 11 and extends well beyond the side edges. It is secured in place to the foundation pad by concealed stitches.

70 Next, two cheek pads 14, 14, (see Fig. 4) of similar material are applied. They also extend well beyond the periphery of the foundation pad 11. I then apply the nose pad 15 (see Fig. 5), a lip pad 16 (see Fig. 6), and a chin pad 17 (see Fig. 7), each of these pads being secured in place preferably by concealed stitches.

75 Next, the stuffing in the form shown in Fig. 7 is covered with a piece of flesh colored Jersey cloth 18 or other suitable material (see Figs. 8 and 9), the same being drawn tightly over the stuffing and tied with thread, as shown at 20 in Fig. 9. The Jersey cloth being elastic, tends to follow somewhat the inequalities produced by the several pads and thus in part to define the features.

80 Next, I insert two nose stitches 22 (see Fig. 11). Then I put in two eye stitches 90 21 at about the junction line between the forehead pad 12 and the cheek pads 14. These eye stitches 21 define the lower margin of the eyes and the upper margin of the cheek. Next, I put in two mouth stitches 95 23 (see Fig. 12). These stitches are not mere dots and are placed at a slight inclination to each other and are very important in giving to the face a life-like expression.

100 Thereafter, I remove the thread 20, loosening the ends of the jersey fabric 19, as shown at 24. (See Fig. 13.) I then push up under the Jersey fabric two additional cheek pads 25 indicated in dotted lines in Fig. 13; also, if required, additional stuffing for the chin. The additional cheek pads are pushed up as far as is permitted by the eye stitches 105 21. This accentuates the swelling of the cheek under the eye and prevents the flat expressionless appearance which ordinarily 110 characterizes a rag doll. In combination with the two straight eye stitches 22, this

construction greatly increases the life-like appearance of the doll.

The Jersey material is then pulled back in place and tied again, as shown at 26. (See Fig. 16.)

The wig is then prepared and consists of a scalp piece 27, hair 28 and brain stuffing 29. This stuffing is necessary to build up the head to the proper shape, giving to it the horizontal or backward length which usually characterizes a baby's head. The wig is then put in place, as shown in Fig. 16. The features are painted in with oil paints, due regard being had to the position of the several stitches. It will be understood that the two eye stitches 21, the lower margin of the eye, the pupils, eyebrows, and eyelashes are properly placed with relation thereto. Thereafter the head is placed on the doll's body, not shown.

In the doll's head construction, as hereinbefore described, the life-like appearance of the features is due chiefly to three things:—(1) the building up of the features by the use of individual pads for the several features secured to a foundation pad which leaves creases or hollows between the several pads into which the Jersey material fits owing to its elasticity, (2) the use of a long stitch in place of a dot or series of short stitches to form parts of the features, and (3) the re-stuffing of the cheeks which pushes up the pad close under the eye producing the shape which is characteristic of a baby's face. It will be understood, of course, that the features are painted in with suitable color combinations.

I find that dolls made as described herein have a life-like appearance equal to or exceeding dolls made from ceramic materials and that they lack the wooden expression which have heretofore been characteristic of rag dolls. I furthermore find that this life-like appearance is due more to the construction described than to the painting, since a doll made in the ordinary manner with the features painted as skillfully as possible will have a wooden appearance and will lack altogether the life-like appearance of a doll made as described herein.

This life-like appearance is largely due to the use of the individual or independent

pads used in building up the several features, as set forth, these pads being all secured in place in the completed head so that they will not become displaced. Also the use of the elastic fabric covering bearing on the somewhat roughly shaped pads tends to soften or draw in the contours of the same and assists in producing the life-like appearance of the completed head.

What I claim is:

1. A head for a rag doll which includes a foundation pad, independent pads all secured in place on the foundation pad and arranged to simulate the several features secured to said foundation pad, and a covering of elastic material.

2. A head for a rag doll which includes a foundation pad, individual pads all secured in place on the foundation pad and arranged to simulate the several features, a covering of elastic material and stitches to assist in defining the features.

3. A head for a rag doll which includes a foundation pad, independent or individual pads, all secured in place on the foundation pad and arranged to simulate the several features, a covering of elastic fabric, stitches to define the features in part and paint applied to the elastic covering to complete the features.

4. A head for a rag doll consisting of a foundation pad and independent or individual pads to represent, respectively, the main part of the head including the forehead, the cheeks, the nose, the lips, and the chin, said pads being all secured in place to said foundation pad, thus preventing displacement thereof, and a covering of elastic fabric over all of said pads.

5. A head for a rag doll consisting of a foundation pad and independent or individual pads to represent, respectively, the main part of the head including the forehead, the cheeks, the nose, the lips, and the chin, said pads being all secured in place to said foundation pad, thus preventing displacement thereof, a covering of elastic fabric over all of said pads, and stitches to assist in defining some of the features.

In testimony whereof I affix my signature.

RUTH MACKAY.
